(57) CLAIM

The ornamental design for a beverage capsule cup, as shown and described.

DESCRIPTION

FIG. 1 is a top perspective view of a beverage capsule cup showing our new design;
 FIG. 2 is a bottom perspective view thereof;
 FIG. 3 is a side view thereof;
 FIG. 4 is a top view thereof; and,
 FIG. 5 is a bottom view thereof.
 In the drawings, the broken lines show portions of a beverage capsule cup and form no part of the claim.
